MAURICE LINFOOT, OF BOCKING BRAINTREE, ENGLAND, ASSIGNOR TO COURTAULDS LIMITED, OF LONDON, ENGLAND.

APPARATUS FOR TREATING ARTIFICIAL-SILK AND OTHER THREADS.

1,229,101.

Specification of Letters Patent. Patented June 5, 1917.

Application filed August 10, 1915. Serial No. 44,769.

To all whom it may concern:

Be it known that I, MAURICE LINFOOT, a subject of the King of Great Britain, residing at The Knoll, Bocking Braintree, in the county of Essex, England, have invented new and useful Improvements in Apparatus for Treating Artificial-Silk and other Threads, of which the following is a specification.

10 The object of this invention is to produce an improved thread more especially from viscose or artificial silk which is adapted for use in weaving whether warp, or weft threads, or for making lace, or for other 15 purposes, making use of an improved apparatus as hereinafter described.

For the purposes of this description we will describe the invention with reference to threads of artificial silk for use as warp 20 threads, from which its application to other threads, and for other purposes, will be readily understood.

Heretofore it has been proposed in the application of sizing, or other liquid, to 25 yarn, to employ guide-rollers, situated between the supply, or let-off roller and the roller which applies the treating liquid, to the yarn, the said yarn being led around the guide-rollers prior to its contact with 30 the roller which applies the treating liquid. According to this invention the threads pass from a supply roller or let-off beam direct to a take-up beam, the threads in their direct passage from one beam to the 35 other, being subjected to a sizing, or dyeing treatment by surface contact with a rotatable roller, or the equivalent, and subsequently to a gradual drying action by being passed over a heated cell having a surface of large superficial area. The threads 40 pass direct from the supply, or let-off roller, to the rotatable roller, which applies the treating liquid, no guide-rollers being employed between the treating-liquid applying roller, and the supply, or let-off roller.

When treating threads according to this invention we prefer to employ threads having the minimum amount of twists, or 50 turns, (say two instead of six or eight per

inch) whereby we obtain threads uniformly sized and stretched, and in the subsequent woven fabric, a more uniform piece of cloth, with the maximum amount of brightness, or luster, and possessing great softness to the touch. 55

In apparatus according to this invention, in order to obtain threads as aforesaid, I so arrange the machine that the threads under treatment shall be passed through approximately in the same plane and in as direct a line as possible so as to cause a minimum amount of strain and at the same time to present each thread readily to the operator's hands. In applying 60 the size to the threads, I cause the threads to pass from the supply or let-off beam direct to and over the upper surface of a roller rotating in contact with a solution of size, thereby avoiding the squeezing of the 65 threads and possibly the breaking of the same. After passing over the sizing roller the threads are caused to pass over a heated surface, or surfaces, consisting of a closed chamber (which is suitably heated for example by steam) having a smooth upper surface of large area over which the said threads pass, but so as not to come immediately into actual contact with the said upper surface during the first portion of their 70 passage, thereby providing for the evaporation of the superfluous moisture from the size and preventing the said threads sticking to the smooth upper surface. The threads pass from the surface of the cell 75 onto the front beam, or take-up roller, which may be provided with pressure rolls, having for their object to obtain a firm, compact warp, of the threads as they are wound thereon. 80

In a convenient form of apparatus according to my invention the threads previously wound on the back warp-beam or let-off roller, hereinafter referred to as the let-off beam, are first passed under a rod, preferably of glass, and then led through a comb and over the sizing roller, so as to obtain a uniform contact as the threads are drawn off. The threads pass from the sizing roller through a reed, and at this stage may be 85 90 95 100

suitably separated vertically by a reed and horizontally by a rod, or rods. The threads next pass over the surface of the steam heated cell and then through a cross-taking reed for putting the threads uniformly on the front warp beam or roller hereinafter referred to as the take-up beam and taking an end-and-end lease. A lifting rod, or lifting rods, preferably of glass may be arranged at, or near, each end, and outside of the heated cell which can be so operated that when the apparatus stops the threads can be raised clear of the hot surface so as to prevent the burning of the said threads or the sticking of the same to the surface of the cell, the rods being lowered again when the machine is restarted. The glass rod between the let off beam and sizing roll may be similarly operated so that the threads may also be lifted clear of the sizing roller when the rotation of the take-up beam is stopped. The raising and lowering of the glass rods, may be effected simultaneously with the stopping and starting of the aforesaid rotation of the take-up beam by means of rods, and links, or the equivalent, suitably arranged and connected to any suitable moving, or movable part of the apparatus; or, the said glass rods may be connected to a common rod, or bar, which may be actuated by the falling of a weight, or weights, to effect the raising of the glass rods, the lowering of the said rods being effected when desired, by the depression of a treadle, or treadles. In order to prevent, or minimize any injurious effect which may arise from the sudden falling of the weight, or weights, a dash-pot, or dash-pots, may be provided, so that the falling of the weight, or weights, is effected gradually. When it is desired to lower the glass rods, the depression of the treadle, or treadles, may be effected from either end, or both ends, of the apparatus, suitable locking mechanism being provided to maintain the treadle, or treadles, in this position against the action of the weight, or weights.

A variable speed driving gear is provided for driving the take-up beam at a gradually decreasing velocity so as to allow for the gradually increasing diameter of the said take-up beam, so that the threads pass through the apparatus at a uniform rate.

Figs. 1, 2, and 3 of the accompanying drawings show in longitudinal section on the line A, B, of Fig. 3, in transverse section on the line C, D, of Fig. 1 and in plan (with parts removed and partly in section) in Fig. 3, respectively, a preferred form of apparatus in accordance with this invention. Fig. 4, is a transverse section on the line E, F, of Fig. 1 showing the release mechanism appertaining to the treadle adjacent to the take-up beam, and Fig. 5 is an end elevation

of the release mechanism appertaining to 65 the treadle adjacent to the let-off beam. Fig. 6 is a side elevation of the driving clutch.

In the apparatus illustrated the threads 1 to be treated are wound on a rotatable let-off beam 2 (see Fig. 1 of the accompanying drawings) mounted in open-topped bearings 3 situated at one end of the apparatus and they are drawn from the said let-off beam, by a rotatable take-up beam, 4, mounted in 70 suitable bearings 5 situated at the other end of the apparatus. The threads 1 are led from the let-off beam, or roller, 2 under a rod 6, preferably of glass, and then through a comb 7 and onto a rotating roller 8 dipping into a trough 9 containing a solution of size which is uniformly applied, by the said roller 8, to the threads as they are drawn thereover. From the sizing roller 8 the threads 1 pass through a reed 10 and they 80 may, if desired, pass over, or under, rods 11 so as to be separated both horizontally and vertically. The threads 1 next pass over the surface of a heated cell 12 which dries them and they then finally pass through a 90 cross-taking reed 13 onto the take-up beam, 4. The surface of the heated cell 12 is preferably of a formation such that the threads 1 do not come immediately into actual contact therewith during the first portion of 95 their passage thereby providing for the evaporation of the superfluous moisture from the size and preventing the threads sticking to the said surface.

Rods 14, preferably of glass, are provided, 100 in proximity to the ends of the heated cell 12, which are adapted and operated to ascend when the rotation of the take-up beam 4 is stopped and lift the threads 1 clear of the said heated cell so as to prevent 105 the liability of the said threads being damaged by burning or by adhering to the said cell and to descend, when the rotation of the said beam is again started, so that the said threads are permitted to come into engagement with the said heated cell. If desired the rod 6 may also be caused to ascend and descend with the stopping and starting of the rotation of the take-up beam 4, so that the threads 1 are out of engagement 115 with the sizing roller 8 (which is preferably constantly rotating) when the said beam is not rotating and in engagement with the said roller when the said beam is rotating. The rods 6 and 14 may be caused to ascend and descend simultaneously with the stopping and starting of the rotation of the take-up beam 4 and this may be effected as hereinafter described.

Rotation of the sizing roller 8 is effected 125 from a pulley 15 (see Fig. 3 of the accompanying drawings) formed in one with a sleeve 16 mounted on a shaft 17, and adapt-

ed to rotate freely thereon, or to be clutched thereto as desired, the said sleeve having also formed in one therewith a pulley 18 to which rotary motion can be transmitted from any suitable power driven shaft. Rotary motion is transmitted from the pulley 15 by a belt 19 (see Fig. 2 of the accompanying drawings) to a pulley 20 secured to a counter-shaft 21 having another pulley 22 secured thereto (see Fig. 3 of the accompanying drawings) from which rotary motion is transmitted, by a belt 23, to a pulley 24, secured to a vertical shaft 25 provided with a toothed wheel 26 gearing with a toothed wheel 27 secured to the shaft 28 of the sizing roller 8.

The pulley 15 constitutes one member of a clutch, the other member 29 of which is slidably secured to the shaft 17, so that when the said clutch members are in engagement, as shown in Fig. 3 of the accompanying drawings, the said shaft is rotated, and this rotary motion is transmitted through a variable speed driving gear 30 to a shaft 31 which acts, by means of a flexible connection, to rotate the take-up beam 4, and this is preferably effected in the following manner: Secured to the shaft 17 is a pulley 32 which transmits, by a belt 33, rotary motion to a pulley 34 secured to a shaft 35 of the variable speed driving gear 30, from which shaft 35 the motion is transmitted to a second shaft 38 of the said variable speed gear by means of a belt passing around expandable coned pulleys 36 and 37, mounted on the shafts 35 and 38 respectively. Secured to the shaft 38 is a pulley 39 which transmits, by a belt 40, rotary motion to a pulley 41 secured to a shaft 42, which in turn transmits its motion, through worm gearing 43, to the shaft 31. A recess 44 is provided in the end of the shaft 31 for the reception of one end of the shaft 45 of the take-up beam, 4, the other end of the said shaft being carried in the open-topped bearing 5. Rotary motion is transmitted from the shaft 31 to the take-up beam, 4, by means of a strap 46, or its equivalent, connected to a crank arm 47, secured to the said shaft 31, and connected to the said take-up beam, in the manner usually adopted for rotating warp-beams, or rollers. The variable speed driving gear 30 may be of any known, or suitable, kind and it may, if desired, be provided with means whereby the speed is caused to be automatically varied in accordance with the amount of threads wound on the take-up beam, 4, so that the said threads are drawn through the apparatus at a uniform rate, or, if desired, hand operated means, such, for example, as shown in Fig. 3, of the accompanying drawings, may be employed for this purpose. A pressure roller 48 suitably mounted on the end of a counter-bal-

anced arm 49 is provided which is adapted 65 to bear upon the threads on the take-up beam, or roller, 4 and causes the said threads to be firmly and compactly wound on the said take-up beam.

Simultaneous movement of the clutch 70 member 29 into, or out of, engagement with its member, whereby the rotation of the take-up beam 4 is started or stopped, and of the rods 14 and 6, whereby the threads 1 are lowered, or raised, as aforesaid is preferably effected as follows: Mounted in suitable bearings on the end of the apparatus carrying the take-up beam, 4, is a shaft 50 (see Figs. 1, 3 and 4 of the accompanying drawings) which is adapted to be turned 80 in one direction by a treadle 51 in opposition to the action of a weight-controlled lever 52 which acts to turn the said shaft in the opposite direction. Secured to the shaft 50 is a lever 53 which is connected, by a 85 link 54 (see Fig. 6 of the accompanying drawings) to a clutch-shifter 55 pivoted to the frame of the apparatus, and engaging, in the usual way, with an annular recess 56 formed on the boss 57 of the longitudinally movable member 29 of the clutch. The arrangement is such that upon the treadle 51 being depressed the said member 29 is moved into its engaging position and the shaft 17 is rotated, and upon the treadle 95 being raised, by the action of the weight-controlled lever 52, the said member is moved into its disengaged position and consequently the rotation of the said shaft is stopped. The apparatus may, if desired, 100 be provided with a treadle 58, at its other end, which is coupled to the treadle 51, so that the apparatus can be operated from either, or both, of its ends. The treadle 58 is secured to a shaft 59 and acts in opposition to the action of a weighted lever 60 similarly to the treadle 51. The shafts 50 and 59 have each secured thereto an arm 61, and these arms are coupled, or connected, together by a rod 62. Arms 63 and 64, secured to a shaft 65 mounted in bearings 66 on the side frame of the apparatus, are caused to be moved into the path of the treadles 51 and 58 respectively, when the said treadles are depressed and by engaging with the upper sides thereof prevent the return of the said treadles to their raised position. The shaft 65 is provided with a weighted arm 67 which acts, when the treadles 51 and 58 are depressed, to turn the said shaft in its bearings whereby the arms 63 and 64 are moved into the path of the said treadles. The shaft 65 can be turned in the direction to effect the release 115 of the treadles by any convenient means, such, for example, as by a hand-lever 68 secured to the said shaft as shown at the take-up beam end of the apparatus, or by a

hand-rail 69 (see more particularly Fig. 5 of the accompanying drawings) pivoted, at one end, to a depending piece 70, secured to the frame of the apparatus, and connected at its other end by a link 71 to an arm 72 secured to the shaft 65 as shown at the let-off beam end of the apparatus.

The rods 6 and 14 are each carried on a pair of rods 73 (hereinafter referred to as carrier rods) vertically movable in holes formed in the side frames of the apparatus and each of the said carrier rods is caused to ascend and descend by a bell-crank lever 74, 75, pivoted to the said side frames. One arm 74, of each of the bell-crank levers is connected to its respective carrier rod by a pin and a slot connection and the other arm 75 of each of the said bell-crank levers on one side of the apparatus are pivotally connected to a bar 76 while the corresponding arm 75 of each of the bell-crank levers on the other side of the apparatus are similarly connected to another bar 77. Mounted on the before-mentioned shaft 50 is a sleeve 78 having secured thereto a weighted arm 79 which controls the lever 52 before referred to, there being a pin and slot, or equivalent connection, between them so that turning movement of the said shaft is transmitted to the sleeve thereon. Secured to the sleeve 78 are arms 80 and 81 which are connected by links 82 and 83 to the bars 76 and 77, respectively, so that by the turning of the sleeve 78 in one direction or the other the bell-cranks 74, 75 are operated to raise, or lower, the carrier rods 73.

Presuming the position of the parts to be that shown in Fig. 1 of the accompanying drawings, by operating either the hand lever 68, or the hand-rail 69, to turn the shaft 65, the arms 63 and 64 are caused to release the treadles 51 and 58 permitting the shaft 50 to turn, by the action of the weighted levers 60 and 79, whereby the clutch member 29 is moved out of engagement with its driving member 15, so that rotation of the take-up beam, 4, is stopped, and, simultaneously therewith, the sleeve 78 on the said shaft 50 is turned and operates the bell-crank levers 74, 75, whereby the rods 6 and 14 are raised and the threads 1 moved out of contact with the sizing roller 8 and the heated cell 12. To restart the apparatus either, or both, of the treadles 51 or 58 are depressed, causing the shaft 50 and the sleeve 78 to turn in the opposite direction, so that the take-up beam, 4, is again rotated and the rods 6 and 14 again lowered to permit the threads 1 to be in contact with the sizing roller 8 and the heated cell 12. Upon the depression of the treadles 51 and 58 the shaft 65 is turned, by the action of the weighted-lever 67, so that the arms 63 and 64 thereon are moved into the path of

the said treadles and prevent them ascend. 65

In order to prevent the weighted levers 60 and 79 descending too suddenly their action may be controlled by a dash-pot and this can be effected, as shown in Fig. 3 of the accompanying drawings, by connecting the arm 81 secured to the sleeve 78 to a plunger 84 of a dash-pot 85 pivotally mounted on the side frame of the apparatus.

The rod 6 instead of ascending and descending with the stopping and starting of the rotation of the take-up beam, 4, as hereinbefore described, can, if desired, be disengaged from its bell-crank lever 74, 75, so that the threads 1 are always in contact with the constantly rotating sizing roller 8, or the said rod may be caused to be raised and lowered sufficiently only to relieve and to apply pressure to the said threads without their actually moving out of contact with the said sizing roller.

Although I have described the apparatus for sizing artificial silk threads for use as warp threads it will be understood that it can be used for sizing threads applicable for other purposes and further the apparatus can be readily used for dyeing threads with or without sizing.

What I claim is:—

1. In apparatus for treating artificial silk, 95 a treating roller, means for feeding a treating liquid thereto, guide means on opposite sides of the roller for holding the threads in contact with a small arc at the top of the roller to insure only momentary contact of 100 the threads with the roller surface as they pass thereover, and automatic means for lifting said guides to move the thread out of engagement with the roller on the halt of the thread feed.

2. In apparatus for treating artificial silk, 105 a let off beam and a take up beam, a treating roll and a drier arranged in the order named between said beams and over which the silk is passed in a substantially straight course, 110 and guide means for holding the silk in contact with only a small arc at the top of the treating roll and for bringing the silk into gradual contact with the drier, and means for automatically displacing said guide 115 means to lift the silk out of contact with the roll and drier on the halt of the feed.

3. In apparatus for treating artificial silk, 120 a treating roller, a heated drier over which the treated threads are passed, and means for automatically lifting the threads out of contact with the treating roller and drier upon the halt of the thread feed, substantially as described.

4. In apparatus for treating artificial silk, 125 a heated drier, means for passing treated threads thereover in contact with portion of its superficial area, guards over which said

threads pass at each end of the drier and means mechanically associated with the thread feed for automatically displacing said guards to lift the threads out of contact with the drier upon the halt of the thread feed.

5 In testimony whereof I have signed my

name to this specification in the presence of two subscribing witnesses.
